UNITED STATES PATENT OFFICE.

HARRY C. ADAM, OF ST. LOUIS, MISSOURI.

DESIGN FOR A HOLDER FOR ILLUMINATING GLASSWARE.

Application filed May 13, 1922. Serial No. 2,227. Term of patent 14 years.

To all whom it may concern:

Be it known that I, HARRY C. ADAM, a citizen of the United States, residing at St. Louis, Missouri, have invented a certain new, original, and ornamental Design for a Holder for Illuminating Glassware, of which the following is a specification, reference being had to the accompanying drawing, forming a part thereof.

The figure of the drawing is a side elevational view of my new ornamental design for a holder for illuminating glassware.

I claim:

The ornamental design for a holder, for illuminating glassware, as shown.

HARRY C. ADAM.
